United States Patent Office.

CHARLES KING, OF MORRISTOWN, NEW JERSEY.

Letters Patent No. 66,359, dated July 2, 1867.

IMPROVED CAR-REPLACER.

The Schedule referred to in these Letters Patent and making part of the same.

TO ALL WHOM IT MAY CONCERN:

Be it known that I, CHARLES KING, of Morristown, in the county of Morris, and State of New Jersey, have invented a new and improved Car-Replacer, and that the following description taken, in connection with the accompanying drawings, hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention relates to a new and improved means for replacing cars upon a railroad track after they have casually run off from the same.

The invention consists of an inclined plane provided with a pivoted rail in connection with another inclined plane without a pivoted rail, both inclined planes being secured to the rails of the track and all arranged in such a manner that an engine or car may be moved or readjusted upon the rails of the track from either side thereof.

The invention also consists in the application of anchors or clamps to the rails in connection with cables or chains and a windlass, all arranged as hereinafter fully shown and described, whereby the engine can, in case of the slipping of the driving-wheels, or the setting of the same between the rails of the track, draw itself upon the latter. In the accompanying sheet of drawings—

Figure 1 is a plan or top view of my invention.

Figure 2, a transverse section of the same taken in the line *x x*, fig. 1.

Figure 3, a transverse section of a portion of the same taken in the line *y y*, fig. 1.

Similar letters of reference indicate like parts.

A A represent the rails of a track, and B B' are two inclined planes, attached to one side thereof by clamps C, as shown clearly in fig. 2. One of these inclined planes B' has a rail, D, pivoted to it, as shown at *a*, and this pivoted rail extends from beyond the lower edge of the inclined plane B' and laps over or upon the rail A to which said inclined plane is attached, as will be fully understood by referring to fig. 1. The other inclined plane B is not provided with a pivoted rail, D, it not being necessary. This office of this pivoted rail, it will be seen, is to carry the flange of the wheel over the rail A, and the object in having the rail D secured to the inclined plane B' by a pivot, is to admit of D being adjusted to either side of B', according to which rail A it is necessary to apply B'. The device therefore may be applied to the track so as to admit of an engine or car being replaced thereon from either side. In case the wheels of an engine slip on the track or when off from the track, in the effort to work itself or an attached car, either or both upon the track, I employ anchors or clamps, and a windlass to overcome the above-mentioned difficulty. The anchors are constructed of metal arms E E, secured horizontally by pivot-bolts *b* in bars F F, which are secured to the inner sides of the rails A A by clamps, G, constructed in any way which will admit of the bars being readily applied to and detached from the rails. Each arm has a cable or chain, H, attached to it by a hook, I, and these cables or chains are secured to a windlass, J, which is placed on the front axle of the engine. By this arrangement it will be seen that the engine will be able to draw itself upon the track or rails.

Having thus described my invention, I claim as new, and desire to secure by Letters Patent—

1. The inclined planes B B', in combination with the pivoted rail D on B', and the clamps C, all constructed substantially in the manner as and for the purpose set forth.

2. The arms or anchors E, fitted or pivoted in bars F, clamped to the rails A A, in combination with the cables or chains H, and the windlass J on the axle of the engine, said parts being arranged substantially in the manner as and for the purpose specified.

CHARLES KING.
